No. 884,622.

PATENTED APR. 14, 1908.

G. A. STAFFORD, I. P. WHITAKER & J. L. LOPP.

ELECTRIC RAILWAY SIGNAL.

APPLICATION FILED JULY 26, 1907.

UNITED STATES PATENT OFFICE.

GEORGE A. STAFFORD, OF BELCHERVILLE, IRA P. WHITAKER, OF ALVORD, AND JOHN L. LOPP, OF GREENWOOD, TEXAS.

ELECTRIC RAILWAY-SIGNAL.

No. 884,622.

Specification of Letters Patent.

Patented April 14, 1908.

Application filed July 26, 1907. Serial No. 385,652.

To all whom it may concern:

Be it known that we, GEORGE A. STAFFORD, residing at Belcherville, in the county of Montague, IRA PASCHAL WHITAKER, residing at Alvord, and JOHN LEMUEL LOPP, residing at Greenwood, in the county of Wise and State of Texas, citizens of the United States, have invented certain new and useful Improvements in Electric Railway-Signals, 10 of which the following is a specification.

Our invention relates to improvements in electric light railway signals; and the object of the invention is to provide means whereby a light can be thrown in a vertical and in a 15 forward direction from the forward end of a locomotive as a signal for other trains, and also in a rearward direction which will enable passengers to see clearly their way in getting on and from a train of cars and manipulating 20 mail and express matter, and a further object is to simplify, improve, and cheapen the cost of construction of our device over the existing prior state of the art.

With these and other objects in view, the 25 invention consists in the novel construction and combination of parts as will be herein-after more in detail described and specifically claimed.

We have fully and clearly illustrated our 30 invention in the accompanying drawings, in which:

Figure 1 is a side elevation of the upper part of a locomotive shown in dotted lines, and also showing our invention applied thereto. Fig. 2 is a front view thereof, showing two receptacles located each side of the boiler of a locomotive. Fig. 3 is a sectional view of one of the lamps or receptacles, and Fig. 4 is a perspective view of the device 40 detached from the locomotive.

Similar letters of reference indicate corresponding parts in the several figures.

Referring to the drawings: A designates a receptacle for incandescent lamps of pear-shaped contour located each side of the boiler of a locomotive and formed in two sections a' and hinged together, as at a^2 , more clearly shown in Fig. 3, the lower section a' forming a reflector a^3 which may be of any 50 suitable reflecting material for reflecting the light from the receptacle through the medium of the incandescent lamp located in the receptacle hereinbefore mentioned and which will be hereinafter more in detail described.

B designates a detachable tube or chimney 55 formed of glass or of any other suitable material adapted for the purpose. This tube or chimney is detachably secured to the apex of the receptacle by means of a set-screw C passed through an opening formed in said 60 receptacle and which bears against the lower portion of the glass tube B.

D designates a stationary horizontal tube, the main portion of which having a bend therein for the purpose of allowing it to fit 65 snugly over the top and forward end of a locomotive to which it is secured, the ends of this tube passed through the side of the receptacle.

E designates a yoke provided with short 70 sleeves e which are secured to the inner sides of the receptacle and which have an oscillating movement upon the ends of the stationary tube D.

F designates an incandescent lamp 75 located in the receptacle A and secured to the end of the tube D from which an electrical conducting wire runs through the stationary tube D to a duplicate lamp located in the opposite receptacle secured to the opposite end 80 of the opposite sleeve of the yoke E and also the opposite end of the stationary tube D. This last mentioned receptacle being a duplicate of the one hereinbefore described, a further description of the same is deemed 85 herein unnecessary.

G designates a pull rod, the forward end of which is secured to the yoke E, its rear or opposite end being secured to a lever H, which in turn is secured at its lower end to the cab 90 of the locomotive, the free end of said lever having a small ratchet lever I secured to its upper end, the lower end of lever I taking in notches in an arc or sector secured to the side of the cab. 95

When necessary to clean the lamp, the lower section of the receptacle is opened and access is allowed for such purpose, and when it relates to the chimney the set-screw is withdrawn and the chimney released, when 100 the chimney may be cleaned also, and then refastened by means of the set-screw.

The electricity can be generated by means of a dynamo adapted for the purpose affixed to the boiler of the locomotive. By the construction of our particular device the rays of light are thrown extremely high so as to enable the engineers to see oppositely coming 105

trains, even from across mountains, so as to avoid head-on collisions which are apt to occur if the signal is not seen in time.

From the foregoing description taken in connection with the accompanying drawings the operation of our device will be obvious.

Having thus described our invention, what we claim as new and desire to secure by Letters Patent is:

- 10 1. A receptacle for holding an incandescent lamp, said receptacle formed in two sections a lamp located in the receptacle, a tube detachably secured to the upper section and the lower section forming a reflector and
- 15 means for reflecting the light vertically and in front and rear of a locomotive, substantially as and for the purposes set forth.
- 20 2. The combination with a receptacle formed in two sections a lamp located in the receptacle, a tube detachably secured to the

said receptacle, the lower section forming a reflector; of a horizontal stationary tube having a bend in the body thereof, a yoke loosely secured to the ends of said tube by means of short sleeves, a pull rod having one of its ends secured to the yoke, and its opposite end secured to a hand lever for adjusting the receptacle to control the rays of light substantially as described.

In testimony whereof we affix our signatures, in presence of witnesses.

GEO. A. STAFFORD.
IRA P. WHITAKER.
JOHN L. LOPP.
